UNITED STATES PATENT OFFICE.

ALBERT H. HEWS, OF CAMBRIDGE, MASSACHUSETTS.

DESIGN FOR RUSTIC HANGING-BASKETS.

Specification forming part of Design No. **7,507**, dated June 30, 1874; application filed March 24, 1874.
[Term of Patent 3½ years.]

To all whom it may concern:

Be it known that I, ALBERT H. HEWS, of Cambridge, in the county of Middlesex and State of Massachusetts, have invented a Design for Rustic Hanging-Baskets, of which the following is a specification:

The nature of my design is fully represented in the accompanying drawing, to which reference is made.

My invention relates to an original design for hanging-baskets, consisting of making such baskets of clay in imitation of a log of wood, as shown in the drawing.

When painted in imitation of nature it produces a very pretty effect, and is especially adapted for hanging in windows, piazzas, and hot-houses.

What I claim as my invention, and desire to secure by Letters Patent, is—

The new and original design for hanging-basket, as herein shown and represented in the accompanying drawing.

ALBERT H. HEWS.
